INCANDESCENT GAS FITTING

Sidney Rayner, London, England, assignor to Falk,
Stadelmann & Company Limited, London, England

Application September 9, 1954, Serial No. 32,219

Term of patent 14 years

(Cl. D48—4)

To all whom it may concern:

Be it known that I, Sidney Rayner, a subject of the Queen of Great Britain, have invented a new, original, and ornamental Design for an Incandescent Gas Fitting, of which the following is a specification, reference being had to the accompanying drawings, forming part thereof.

Fig. 1 is a perspective view of an incandescent gas fitting, showing my new design.

Fig. 2 is a sectional view taken on the line 2—2 of Fig. 1 looking in the direction of the arrows.

The dominant features of my design reside in the portions shown in full lines.

I claim:

The ornamental design for an incandescent gas fitting, as shown and described.
